COSMETIC APPLICATOR WITH
SHRINKPROOF FIT

John W. Anderson, Newtown, Conn.

Application May 16, 1944, Serial No. 535,779

5 Claims. (Cl. 206—56)

1

This invention relates to improvements in a handle-like applicator or expellant holder adapted to carry a body of dispensable substance for example a cosmetic stick of any kind, as lipstick, and pertains more particularly to a holder of the general type disclosed in my copending application, Serial No. 467,573 now eventuated in Patent No. 2,419,526. The term "lipstick" as used herein refers to any carried body of medicinal, hygienic, cosmetic or marking material, whether or not in stick or pencil form.

A general object of the invention is to reduce the elaborateness of tool equipment and the number of machine operations required to manufacture and assemble the subject article from parts of all-plastic material; also to reduce the amount of skilled labor required in such manufacture; also to enable major parts of the applicator to be made of inexpensive grades of "plastic" materials without sacrificing the permanence of workable fits between the parts and otherwise satisfactory operation. The term plastics, or plastic materials, as used herein refers to all moldable forms of synthetic resins, casein and any other non-metallic substances which possess varying abilities to maintain permanently the shape and size in which they are originally produced by the mold especially when molded into thin walled, hollow, or shell-like shapes.

A particular object of the present improvements is to eliminate the necessity for edge turning operations formerly contemplated as means for forming retaining lips on telescopically related parts and to provide, instead, interfitting shapes and relative sizes of resilient tubular parts affording enough expansive "spring" to enable such parts to be snapped into and out of automatically maintained working assemblage by simple hand manipulation.

A contributory object is to secure fixedly together certain parts composed of molded plastic material through adherence and interlocking fits, this being an assembling expedient that also reduces the need for skilled labor and production tool equipment.

A further object is to make use of relatively low cost "plastics," subject to considerable self-shrinkage or distortion, as the material composing an outer removable cover cap for an all-plastic lipstick holder, and to accommodate uncontrolled shrinkage and warpage of such cover cap in a manner to prevent it from seizing or binding on interior parts over which it is sleeved into place.

A particular object is to provide spot spacers

5 to take up an unusual amount of diametral looseness or play between the closed end of a loosely fitting cover cap and the resilient open end of a lipstick casing shell over which such cap is sleeved into place, and to afford additional external steadyng restraint for the opposite or open end of such cover cap near the rigid or reinforced end of such casing shell.

10 Still further objects of the present improvements are to protect by effective shielding means the stick ejecting and retracting telescopic core mechanism from becoming clogged by crumbs that may drop from the soft material of the lipstick, and to utilize a special shape of closed end 15 for the removable cover cap to help maintain the nose or applicative end of the lipstick central of the cover when not in use, thereby to prevent the highly colored lipstick paste from becoming daubed on the interior side walls of the cover or becoming daubed on the exterior of the walls of the casing shell, which latter must be contacted by the user's fingers in manipulating the lipstick holder.

20 Examples of means afforded by these improvements for attaining the foregoing and other objects will become clear in greater detail from the following description of a representative embodiment of the invention in which description reference is had to the accompanying drawings, 25 wherein:

Fig. 1, drawn on an enlarged scale, shows a complete lipstick applicative holder and cover cap sleeved thereon, both being longitudinally sectioned on a central plane.

30 Fig. 2 is a plan view taken in section on plane 2—2 in Fig. 1 crosswise the assembled lipstick holder and cover cap.

Fig. 3 is a fragmentary sectional view like Fig. 1 drawn on a reduced scale with cover cap removed showing the lipstick projected for use.

35 Fig. 4 shows the removed cover cap with partially broken away wall.

Fig. 5 is an exploded view of the telescopic core parts of the expellant holder, the cover cap being omitted.

40 In the cosmetic applicator of my aforesaid Patent No. 2,419,526, it is proposed to provide a telescopic assemblage of hollow overlapping tubular parts combined to form in effect a longitudinally extensible and collapsible telescopic shaft or articulated core structure for transmitting turning movement from an outside finger operated ferrule to an inside lipstick carrier cup while such cup slides with a screw motion toward 45 and away from such ferrule within a helically

3

grooved casing shell on which the ferrule is free to swivel. The construction herein described makes use of molded all-plastic parts in an assemblage of like nature and does not require for continued satisfactory operation absence of warpage or shrinkage in the originally molded shape of such parts.

In the illustration herein of one form of the improvements an outer tubular casing shell 10 is, before assembly, open at both ends. Its base end is molded to a shape that affords an external annular stiffening flange 11. A helical groove 19 is sunk in the internal face of casing shell 10 which groove is dead-ended at 20 near the top of the shell but opens freely outward through the flanged bottom end of the shell at 21. Preferably shell 10 is molded from a relatively high grade of plastic material that is fairly immune to warpage and shrinkage after coming from the mold. Also the grooved cylindrical wall or barrel portion of this casing is for the most part of substantial thickness which imparts permanence to its original shape and size. In other words the barrel portion of casing 10 is relatively stiff and rigid.

In the interest of lowered cost of material and product, the features of construction that are novel herewith enable other major parts of my improved lipstick holder to be molded from less costly grades of "plastic" materials by economical molding processes, even though less immune to self-change of shape and size as they cool or dry and age. To accomplish this, I have devised a structural relationship of such cheaper plastic parts to the afore described casing shell which permits considerable warping distortion and shrinkage of the former without bringing into play difficulties that heretofore have been encountered with fits and relative movements of the parts after assembly.

The ferrule 16 is molded to a cup shape affording a resilient annular wall 15 composed of a thickened ring-like throat section 12 having a relatively small internal girth interposed between an annular internal groove 14 and a terminal "counterbore" 24 both having larger internal girths. The bottom end of ferrule 16 is closed by a solid base wall 17 centrally in whose interior face there is sunk a shallow straight-sided recess or socket 22. The annular edges 23 and 23' at the junction of throat section 12 with counterbore 18 and with groove 14, respectively, are chamfered or beveled to facilitate the manual forcing of the end flange 11 on casing shell 10 in an axial direction past throat section 12 into or out of groove 14 for purposes of snap assemblage and disassemblage. Ferrule wall 15 at the groove 14 is sufficiently thin and resilient to yield and permit slight spreading of throat 12 for enabling the oversize flange 11 to pass throat section 12 and will immediately spring back into the assembled relationship shown in Figs. 1 and 3 and thereby imprison flange 11 rotatably in groove 14. The ferrule 16 and the casing shell 10 may thus be coupled together in freely swiveling relationship without the use of tools and without setting or otherwise permanently changing their original molded shapes for assembly purposes.

The cup-like carrier 25 for lipstick 30 lies inside the helically grooved inner surface of the cylindrical wall of casing shell 10 and is guided by contact therewith in its reciprocative screw-like travel lengthwise of the holder. However, in the present construction, this carrier cup may have a fairly loose fit in relation to the casing shell

4

permitting sufficient diametral play to avoid likelihood of binding from the effects of distortion or warping of the carrier cup. This enables the cup to be molded from cheaper grades of "plastics." The base of the carrier cup contains a well 32 of smaller girth than the diameter of the base of the lipstick, thus forming an annular shoulder 31 on which is seated a thin disk 33, preferably of transparent material. The bottom end of lipstick 30 rests on disk 33 and the latter will preclude crumbs falling from the material of the lipstick from entering well 32 and clogging the underlying relatively movable parts. Well 32 opens downward through a straight sided aperture 34 of smaller cross sectional size than the well itself so that a marginal shelf 38 is formed bordering aperture 34.

Occupying aperture 34 with a free axially sliding fit therein is the straight sided shank of a tubular or hollow coupling 21 which is open at both ends. This coupling may be molded from plastic material to form an outward directed straight-sided head flange 37 slidably fitting well 32. The hollow interior of tubular coupling 21 forms a well 41 extending nearly throughout its length, this well opening downward through a straight sided aperture 42 of smaller cross sectional size than well 41 so that a marginal shelf 36 is formed bordering aperture 42. Aperture 42 affords a free axially sliding fit for the straight sided shank of a rotary impelling post 18 rigid with ferrule 16 having an outward directed head flange 35 slidably fitting aperture 42 and the bottom end of whose shank snugly fits the recess or socket 22 and is secured therein by some suitable adhesive.

Referring now to new features in the slip cap or cover member 13, the same is purposely molded to have an inside diameter and girth unusually large and oversize in proportion to the outside diameter and girth of the barrel of casing shell 10. For example where the casing shell is approximately $\frac{5}{8}$ " in diameter the cover cap may be so oversized as to provide $\frac{3}{2}$ " diametral clearance or play in the normal annular clearance space between cap and casing shell. This is an example of ample clearance to accommodate shrinking of the cover cap and its warping out-of-round even if the wall of the barrel portion of the cap is only $\frac{1}{64}$ " thick and hence limber and resilient, and even though such wall is molded of inexpensive, shrinkable and self-warping molded plastic material. However, I prefer to mold the end wall at the head of the cap to a relatively thick dimension and to form a centrally localized inverted bowl-shaped recess 28 in such end wall for centralizing the applicative end of the lipstick when the cap is in place on the casing shell. Cover cap 13 is further provided with spot spacer projections or inwardly directed axially elongated and circumferentially slender ridges 29 of which there may be three, circumferentially spaced. Ridges 29 takes up the radial clearance between cover cap 13 and casing shell 10 in a region located preferably near the unreinforced open end of the latter and somewhat removed from the end wall of the cover cap in which region there exists the maximum combined ability of both the casing shell and the cover cap to yield if slightly wedged apart by intervening ridges 29 so that a light nongrabbing frictional cling is set up when these ridges slide into contacting engagement with the casing shell as shown in Fig. 1. The cap walls are free to distort in a manner to permit slight radial spreading displacement of the

spot spacers or ridges 29 for this purpose. This centers and steadies the cap in relation to the casing shell at the applicative end of the lipstick holder. At the base end of the lipstick holder the open end of cover cap 13 enters the annular channel provided around the casing shell 10 by counterbore 24 and has a circumferential slip fit with the overlapping wall 15 surrounding counterbore 24 of ferrule 16 whereby it is further steadied with light clinging fit so that the cover cap stays dependably in place on the holder while the applicator is being handled or carried about in a pocket book with other toiletries. While this is true, there is nevertheless plenty of room between the cylindrical walls of cover cap 13 and casing shell 10 for the former to shrink or warp out-of-round without appreciably altering the tightness of the frictional cling exerted by the spot spacers 29 upon the open end of the casing shell, whereby seizing between the parts is prevented from occurring even when considerable shrinkage and warping takes place.

The operation of a lipstick applicator incorporating these improvements will be obvious. The cover cap 13 is first removed and the ferrule 16 is ordinarily clutched against the base of the index finger with the second finger flexed about it to keep the ferrule from turning. The thumb and tip of the index finger of the same hand are thereupon left free to swivel the casing shell 10 about its own axis relatively to the ferrule. Thus the lipstick 30 can be caused to move back and forth between its projected position in Fig. 3 and its retracted position in Fig. 1. Also, with the applicator so manually held, the extent of projection of the lipstick beyond the open mouth of the casing shell can be maintained or varied while the lipstick is being applied.

If the lipstick is not fully retracted when the cap is restored to place as shown in Fig. 1 then the cap recess 28 will thrust against the end of the lipstick and urge the stick carrier 25 to retract farther while such recess keeps the applicative end of the lipstick centered instead of thrusting it to one side which might result in daubing the open end of the casing shell with the substance of the lipstick which would then be liable to stain the hands of the user or any other article contacted by the open end of the holder.

Among the advantages of the foregoing described construction is the greater ease of grasping the ferrule rim 15 between the base of the index finger and the second finger without unintentionally at the same time grasping to some degree the casing shell 10 which would hinder the freedom of the casing shell to be turned by movements of the tips of index finger and thumb. The larger diameter of ferrule relative to the diameter of the casing shell as well as the considerable axial length of the ferrule accounts for this increased ease of one-handed operation.

It will be evident to those skilled in the art that parts differing in shape, size and arrangement from those herein shown can be arranged to operate on similar principles and yield the advantages arising from the particular constructions herein illustrated to explain the invention. Hence the appended claims comprehend and are intended to cover all fair equivalents for the claimed construction that are taught or suggested by the disclosure hereof.

I claim:

1. In a cosmetic holder a manually separable assemblage of relatively swiveling molded plastic

parts including an open ended tubular casing member having an external flange at its open end, and a cup-shaped ferrule member having an annular rim wall encompassing said open end of said casing member and containing an internal annular groove receptive to said flange, said groove being separated from the free edge of said rim wall by a throat section of said ferrule member slightly smaller in diameter than the periphery of said flange, and said rim wall possessing sufficient resilience to permit said flange to be thrust manually past said throat section and into said groove by the mere force of an operator's hand.

15 2. In a lipstick holder, a case having an externally flanged end, a slip cap having an open end oversized in relation to said case, a cupped ferrule operatively associated with said case and cap having a base wall and axially adjacent girths of 20 respectively differing internal diameters including a relatively large girth nearest said base wall defining a groove occupied by said flanged end of the case and a relatively smaller girth next farther from said base wall defining a throat 25 smaller than said flanged end of the case operative to retain the latter in said groove and a relatively larger girth still farther from said base wall, together with an annular shoulder between said throat and the last said relatively larger 30 girth cooperative with the latter to define an annular socket receptive to said open end of the slip cap and adapted to hold the latter steady and central with respect to said case.

3. A cosmetic holder including an open ended 35 tubular casing member having a relatively stiff barrel, and an open ended tubular cap member having a relatively limber barrel, said barrels being telescopically assembled and relatively sized to provide clearance space therebetween, a ferrule 40 swiveling on and closing one end of said casing member, a cross wall closing one end of said cap member, circumferentially separated spot spacers carried by and rigidly on the limber barrel of said cap member in position to span said 45 clearance space near the open end of said casing barrel, and a cup-like formation on said ferrule providing a rimmed annular channel about said casing member receptive to the open end of said cap member, said cup-like formation including 50 a rim encompassing said casing member and sufficiently large in girth to provide between said rim and said barrel of the casing member an annular channel bordered by said rim and by said barrel of the casing member at least as wide 55 radially as the combined radial extent of said clearance space and the wall thickness of said cap member barrel at the latter's open end.

4. In a cosmetic holder a manually separable 60 assemblage of relatively swiveling molded plastic parts including, an open ended tubular casing member having an external flange at its open end, and a cup-shaped ferrule member having an annular rim wall encompassing said open end of said casing member and containing an internal annular groove receptive to said flange, said groove being separated from the free edge of said rim wall by a throat section of said ferrule member slightly smaller in diameter than the periphery of said flange, and said rim wall possessing 65 sufficient resilience to permit said flange to be thrust manually past said throat section and into said groove by the mere force of an operator's hand, there being cooperative shoulder edges respectively on said casing flange and on said throat

section of the ferrule beveled at meeting points of said flange and said throat section in a manner to facilitate forced passage of said flange past said throat section into and out of said annular groove.

5. In a cosmetic holder a manually separable assemblage of relatively swiveling molded plastic parts including, an open ended tubular casing member having an external flange at its open end, and a cup-shaped ferrule member having an annular rim wall encompassing said open end of said casing member and containing an internal annular groove receptive to said flange, said groove being separated from the free edge of said rim wall by a throat section of said ferrule member slightly smaller in diameter than the periphery of said flange, and said rim wall possessing sufficient resilient flexibility to permit said flange to be thrust manually past said throat section and into said groove by the mere force of an operator's hand and having a sufficiently reduced thickness at said annular groove to produce said resilient flexibility thereby to enable said throat section to spread slightly for passing said casing

flange without undergoing a permanent change in size.
